STEREOTYPE MATRIX MOLDING AND
DRYING PRESS

William F. Huck, Richmond Hill, N. Y., assignor
to Irving Trust Company, permanent trustee
for R. Hee & Co., Inc., New York, N. Y., a cor-
poration of New York

Application June 7, 1933, Serial No. 674,648

1 Claim. (Cl. 101—12)

This invention relates to certain improvements in stereotype matrix molding and drying presses, and more particularly to a porous pressure plate through which moisture from the wet matrix will 5 permeate while the matrix is being formed and dried in the press.

In the process of forming a stereotype matrix, a considerable amount of moisture is released from the wet matrix, which has to be absorbed 10 or passed off to the atmosphere. The common practice has been, in the first instance, to absorb this moisture through a number of felt blankets which are inserted, together with the type form and matrix pulp layer, into the press, but the 15 process of completing a matrix according to this practice was usually slow, due to the concentration of moisture in the blankets which retarded the drying action of the matrix and required the drying of all blankets after each operation.

20 In the second instance a metal plate is used which has grooves on one or both of its upper and lower surfaces, with vertically disposed openings connecting said grooves, whereby moisture was permitted to pass therethrough to the atmosphere. This practice offered some improvement 25 over the first form but on such plates where grooves appeared on the lower surface the form of the groove would appear on the surface of the matrix when subjected to high pressure.

30 The escape of moisture was also inclined to be slow due to the limited amount of open space left by said grooves and openings.

The structure according to this invention comprises a pressure plate which consists of a multiplicity of non-corrosive wire mesh sheets, stacked to form a laminated structure, and are supported by a suitable frame. Said pressure plate is then clamped to the press head and one or more blankets are placed over the layer of wet matrix 40 pulp lying over the type form on the press platen.

When the press is operated, the conduction of heat from the platen to the type form will rapidly evaporate all the moisture in the mat and the steam will penetrate through the single blanket 45 to the pressure plate above. Since the pressure plate comprises layers of wire mesh, the entire plate is thereby made porous and the moisture will pass rapidly from the blanket, through the pressure plate and into the atmosphere. It is 50 desirable, however, to apply heat to the pressure plate through the press head to prevent any condensation occurring therein, which would ordinarily occur if the pressure plate was cold.

It is therefore the object of this invention to 55 provide a metallic pressure plate for matrix mold-

ing and drying presses which is porous enough to permit moisture to quickly pass therethrough, which has flexibility and which provides a substantially smooth surface for contact with the blanket to prevent marking of the matrix under pressure.

With the above and other objects not specifically referred to in view, the invention consists in certain novel parts, arrangements and combinations which will be fully described in connection with the accompanying drawing and the novel features pointed out in the claim hereunto annexed.

In the drawing which discloses a preferred embodiment of the invention:

Figure 1 shows the main portions of a matrix drying press to which the invention is applied, certain parts being shown in section, the parts required to form a matrix being shown also in section;

Figure 2 is a section through a completed pressure plate with part broken away;

Figure 3 is a fragmentary perspective view showing one corner of a sheathing which is used to bind the wire mesh sheets together, and showing the sheets partly broken away; and

Figure 4 is a fragmentary plan view showing one corner of the pressure plate.

The pressure plate designated generally by the reference character 11, Figure 2, comprises a multiplicity of non-corrosive fine wire mesh sheets 12, stacked as shown and bound together by means of a sheathing 13. Said sheathing may be constructed in any desired manner, a preferred form being shown in Figures 2 and 3 which consists of two wire mesh covers, an upper cover 14 and a lower cover 15, each cover having a dished portion 16 and a flange 17 extending around the periphery thereof.

The pad of wire mesh sheets 11 is placed within the dished portions 16 of the covers 14 and 15, as shown in Figure 2, and two frame members 18—18 placed above and below the adjacent flanges 17 are secured together by screws 19, thus binding the entire structure together. The frames 18 reinforce the pressure plate without impairing the flexibility of the wire mesh sheets 12, which preferably extend above and below the surfaces of said frames.

It is obvious that a pressure plate of this character will be a highly porous structure since the mesh formation of each of the sheets 12, even though closely packed together, will provide a certain amount of clearance between each mesh portion, through which moisture can easily pass.

In Figure 1 the pressure plate is shown mounted in a press with the associated parts in the matrix molding and drying position. The press parts shown comprise a head 21 and a platen 22 either 5 or both of which may be heated in any desirable manner as by electric heater indicated by numeral 20. The usual form of chase 23, with its type form 24 set up within it, is placed upon the platen 22, and a layer of moist matrix paper 25 10 is laid over said type form. Above said paper a single blanket 26 is placed, the use of which is desirable for its cushioning effect on the matrix 25. The pressure plate 11 may next be placed 15 on top of the blanket if desired, but it is preferably clamped directly to press head 21 by means of suitable clamps 27.

In operation the heat of the platen 22 is conducted through the type to evaporate the moisture in the matrix 25. Said moisture is absorbed 20 by the blanket 26 and then escapes to the atmosphere through the porous pressure plate 11, which plate is heated by conduction of heat from the press head 21. The heat being thus applied from both above and below does not permit conden-

sation of said moisture and due to the ease in which the moisture, in the form of steam, penetrates said blanket and pressure plate, the time for drying the molded matrix is greatly reduced.

While the invention has been shown and described in its preferred form, it will be understood that certain changes and variations may be made in the specific structure provided for carrying out the invention without however departing from the spirit of the invention as defined in the appended claim. 10

What I claim is:

A pressure plate for a matrix drying press comprising a multiplicity of superimposed wire mesh sheets, a closure for said sheets including upper 15 and lower wire mesh sheathing members adapted to completely surround said sheets, an extending flange forming the periphery of each sheathing member, said flanges having their inner faces abutting, and two reinforcing frames arranged 20 over said flanges and adapted to be secured together to clamp the flanges therebetween.

WILLIAM F. HUCK.
